PISTOL

William Andrew Little, Ottawa, Ontario, Canada

Application May 4, 1956, Serial No. 41,344

Term of patent 3½ years

(Cl. D30—1)

Fig. 1 is a perspective view of a pistol embodying my new design; and

Fig. 2 is a rear elevational view thereof.

The essential features of the pistol reside in the solid line portion.

The other side of the pistol is substantially identical to that shown in the drawing.

I claim:

The ornamental design of a pistol, as shown and described.
